No. 11,535.

PATENTED AUG. 15, 1854.

G. SPENCER.
CAR WINDOW.

UNITED STATES PATENT OFFICE.

GEORGE SPENCER, OF UTICA, NEW YORK.

RAILROAD-CAR WINDOW.

Specification of Letters Patent No. 11,535, dated August 15, 1854.

To all whom it may concern:

Be it known that I, GEORGE SPENCER, of the city of Utica, county of Oneida, and State of New York, have invented a new 5 and Improved Window to Aid in the Ventilation of Railway-Cars; and I hereby declare that the following is a full, clear, and exact description of the construction and operation of the same, reference being had 10 to the annexed drawing, making part of this specification, in which like letters refer to like parts.

The nature of my invention consists in providing a revolving window (that may 15 be easily and conveniently managed by the passengers within the car,) and which may be readily placed in a position to leave an opening for the egress of the air, at the forward side of the window, in whichever 20 direction the car may be moving, while at the same time the residue of the window will be closed; and which, by turning the sash a quarter of its circle around, will leave the entire window closed. A convenient 25 means is also afforded for opening one half of the entire window, for the admission of air from without when desired.

A, B, in the annexed drawing, represents 30 a face view of the window as seen within the car, including a section of the car-frame, D, E, F. The window may be inserted as a substitute for, and in the place now occupied by, the windows of cars now in use, and the outer and inner panel-work G, H, 35 I, K, may be made to fit the cars now used.

L, M, N, is a revolving sash turning on the center-pin O. It is circular, with the exception of the clip P. The sash is made in two parts which are connected by the 40 hinges R. The part M, N, being part of a circle smaller than that of the inner panel, is capable of being opened inward, and is held in its place, when closed, by the small slide-bolt S, which is to be disengaged whenever 45 it is desired to open the window and at other times it runs around the entire circle, between the outer and inner panels. That part of the sash which has the clip (P) is of a circle larger than that of the 50 inner panel-work, and runs between the outer and inner panels around the entire circle.

W is a stationary bar extending across the frame, from the top to the bottom, and 55 supports the axis O, on which the sash revolves.

a is a part of the outer panel-work, (stationary) and intended to cover the opening P, when the clipped side of the sash is turned downward, forming the under side of the circle. The whole of the sash as thus described is to be glazed either with two panes of glass corresponding with the openings shown in the drawing, or in smaller divisions as desired.

Thus it will be perceived that the sash L, M, N, may be revolved, in either direction, quite around the circle at pleasure, leaving the opening P, in any position desired except at the bottom of the window, and that when it is at that point, the window will be entirely closed. When the opening P is in the forward part of the window, (toward the locomotive,) the car being in motion, a current of air escapes outward at that part 75 of the window, from the interior of the car, while the rear of the window, at which the dust enters when the car is in motion, remains covered.

The object above described may also be, 80 in part, effected, by attaching a narrow fan-sash at each side of the ordinary window, so that either fan-sash may be opened, leaving a small opening at the forward part of the window, according to the direction of the 85 movement of the car; or sashes may be arranged to slide horizontally either way, into the car frame.

It has long been known that if an ordinary car-window is opened (sliding up, vertically, in the usual way) when the car is in motion, a draft of air is occasioned outward from the interior of the car, at the forward part of the window; and that there is also a strong current filled with dust and 90 cinders, entering at the same time, at the rear of the window. I am also aware that deflectors—blinds, slats, windows, &c.—have been attached to cars, for the purpose of turning off the external pressure of the air, 95 so that an outward current is, by such extra means, established at the rear of the window. But such deflectors, if windows, cannot be opened far enough to keep the cars at the stations comfortable, in very warm 100 weather; and they also present a mechanical disadvantage when there is a strong wind with the cars, until the speed of the cars is greater than that of the wind. They are moreover liable to breakage in passing 110 bridges, piles of lumber, wood, &c.

I desire it to be understood, therefore,

that I do not claim as original, the establishment of an outward current from within in the car, nor that this result is peculiar to my construction of a car-window. 5 Neither do I claim the use of deflectors in any form whatever, as none are attached by me to any part of the car.

I am also aware that circular windows, to be revolved, and having their bearing at 10 the center, have long been known and used to ventilate churches and other public buildings. But whenever those windows are opened to the smallest extent, the opening reaches from the circumference to the center 15 and could not, therefore, be used to accomplish the objects for which my window is intended. For it is well-known that an opening extending to the center of a railway car window would allow a strong current of air to enter laden with dust and 20 cinders, the precise annoyance to be guarded against. I therefore disclaim the original

invention and application of a circular revolving window, and also the bearing upon 25 which it is revolved.

What I claim as my invention and desire to secure by Letters Patent is—

The combination with the side of a car of a revolving window consisting of two, 30 separate, circular sashes connected by hinges, so that one sash may be opened to its full extent, and having a small part of the circle cut off, so that, by revolving it upon its center, a small opening may be 35 made at the forward part of the window, whichever way the car may be moving, the residue of the window remaining at the same time, covered; substantially as described in the foregoing specification.

GEO. SPENCER.
